UNITED STATES PATENT OFFICE.

JOHN L. MCKOWEN, OF SAPULPA, OKLAHOMA.

WATER CIRCULATION UNIT FOR BOILERS.

Application filed May 15, 1922. Serial No. 561,069.

To all whom it may concern:

Be it known that I, JOHN L. MCKOWEN, a citizen of the United States, residing at Sapulpa, in the county of Creek and State 5 of Oklahoma, have invented certain new and useful Improvements in Water Circulation Units for Boilers; and I do declare the following to be a full, clear, and exact description of the invention, such as will 10 enable others skilled in the art to which it appertains, to make and use the same.

This invention relates to an improved water circulation unit which is adapted for disposition in the fire box of a locomotive 15 boiler for permitting the water in the main chamber to circulate therethrough and be further heated.

The object of the invention is to generally improve upon units of this class by providing 20 one of extreme simplicity and durability which is composed of easily procurable pipes and couplings to render the same as inexpensive as possible.

Specifically speaking, it is another object 25 of the invention to provide a circulation unit of this class which is substantially U-shaped in design, being intended to be positioned on one side of the fire box over the grate so that the flame will directly impinge 30 upon it to heat it to an extremely high degree, there being a drain pipe associated therewith and extending through the rear end of the boiler so as to permit it to be drained by this pipe.

35 Other objects and advantages of the invention will be apparent during the course of the following description.

In the accompanying drawings forming 40 a part of this specification and in which like numerals are employed to designate like parts throughout the same:

Figure 1 is a central longitudinal vertical section view through a conventional type 45 of boiler showing one of the improved circulating units installed.

Figure 2 is a transverse section taken substantially on the plane of the line 2-2 of Fig. 1.

In the drawings, the boiler is designated 50 generally by the letter B and as is usual, one end of this boiler is enlarged and the fire box F is located in this enlarged end, having its walls spaced from the walls of the boiler to provide a water space S. The 55 main water chamber C is as is usual, located in advance of the fire box.

As before indicated, the invention resides in the employment of novel water circulation unit which is adapted for disposition in the fire box over the grate, the same being designed for connection to the inner faces of the vertical sides of the fire box and having communication with the main water chamber and water space. Each unit in its preferred form is constructed from spaced 60 horizontally disposed conduits or pipes 1 which have their open ends extended through the flue-sheet of the fire box so as to enable the water in the main chamber to circulate therethrough. As before pointed 65 out, the unit is substantially U-shaped. By referring to the opposite ends of the conduits, it will be seen that they are equipped with elbows 2 carrying very short pieces of 70 pipes 3 and that these pipes are connected with the adjacent vertical extensions of a four-way coupling 4. By referring to Fig. 2 it will be seen that the side horizontal connection 5 of this coupling is connected with the adjacent side wall of the fire box and 75 opens up communication of the unit with the water space S. The remaining extension 6 of the coupling which is disposed toward the rear and has a pipe 7 connected thereto and extended through the rear end 80 of the boiler, this pipe being adapted for connection with a blow-off valve (not shown) and serving in some instances to enable the boiler to be drained.

In operation, it will be seen that the 85 water from the main chamber C of the boiler will circulate continuously through these circulating units and will consequently become additionally heated to a very high degree by the flames from the fire which continuously play on the unit.

By carefully considering the description on connection with the drawings, persons familiar with devices of this class will doubtless be able to obtain a clear understanding 90 of the invention. Therefore, a more lengthy and detailed description is deemed unnecessary.

I claim:

The combination with a boiler including 105 a fire box surrounded by a portion of the boiler proper to form a water space around the fire box; of a pair of substantially U-shaped circulation units for heating the water passing therethrough, 110 said units being supported on the inner faces of the vertical sides of said fire box

over the grate, each of said units being composed of a pair of horizontally disposed spaced pipes connected at their open ends with the flue-sheet of the fire box and connected together at their opposite ends by a four-way coupling, a short pipe connected with the side extension of the coupling and

leading to the aforesaid water space, and a combined drain and blow-off pipe connected to the rear extension and passing through 10 the rear end of the boiler.

In testimony whereof I have hereunto set my hand.

JOHN L. McKOWEN.
